UNITED STATES PATENT OFFICE.

MARCEL PERREUR-LLOYD, OF BOULOGNE-SUR-SEINE, FRANCE.

ELECTROLYTIC APPARATUS.

1,073,868.

Specification of Letters Patent. Patented Sept. 23, 1913.

Original application filed March 28, 1912, Serial No. 686,826. Divided and this application filed October 2, 1912. Serial No. 723,495.

To all whom it may concern:

Be it known that I, MARCEL PERREUR-LLOYD, a citizen of the Republic of France, residing in Boulogne-sur-Seine, Seine, France, have invented certain new and useful Improvements in Electrolytic Apparatus, of which the following is a specification.

This invention relates to an apparatus for carrying out a process for the production of copper by electrolysis by means of solutions obtained by the lixiviation of copper ores, these solutions being always impure and being especially charged with iron in the state of ferric salts, which process is set forth in my U. S. application, Serial No. 686,826, filed March 28, 1912, of which the present application is a division.

The improved process set forth in said application is applicable to all solutions of sulfates, chlorids and other salts of copper, but reference will be made more particularly in the following description to sulfate solutions by way of example.

A preferred form of an apparatus is illustrated in the accompanying drawings, wherein—

Figure 1 is a transverse section, and Fig. 2 is a longitudinal section.

The electrolytic apparatus comprises a tank of wood, or other suitable material in which are supported a number of rectangular or square electrodes, the anodes A, B and cathodes C being arranged alternately. Each of the anodes comprises a rotating center portion in the form of a disk B, the remainder A of the anode being stationary and being suspended from a suitable supporting bar α secured to the top of the tank, the supporting bars α being also connected to the positive terminal m of the apparatus. The stationary portions of the anodes are held in position at their base by means of strips of ebonite or other suitable material D within slots in which the lower edges of the anodes rest. The disks B constituting the movable portions of the anodes are mounted on a horizontal shaft O carried by ball bearings d fixed upon stirrups E, the shaft passing through suitable stuffing boxes c so as to prevent leakage of the electrolyte.

The disks are preferably secured to the shaft by means of washers or sleeves of hardened lead b mounted upon the shaft

and attached to the disk. The cathodes are similarly supported in the ebonite strips D at the base of the tank and are suspended at their upper edges by means of hooks e secured to a horizontal bar n forming the negative terminal of the apparatus. The cathodes which may be of copper or any other suitable metal, can be arranged in very close proximity to the movable anodes so as to obtain a maximum effective surface for a predetermined bulk.

The movement of the rotating disks is transmitted to the electrolyte which may be solution of copper sulfate with sulfur dioxide dissolved therein so that its whole mass is properly agitated and circulated between the electrodes. The tank is preferably provided with a cover in order to avoid loss of sulfurous acid by evaporation. The anodes are preferably composed of lead but if it is desired to economize electromotive force, carbon anodes similarly arranged may be employed.

It is found in practice that with the improved apparatus the amount of electric energy required per kilogram of copper deposited may be reduced to less than 1 kilowatt hour.

In the operation of the apparatus the rapid movement of a portion of the anodes and the agitation of the electrolyte resulting therefrom are favorable to the depolarization and consequently the production of sulfuric acid which may be ultimately utilized for the production of the copper sulfate solution which is used in the apparatus.

The production by electrical means and on the spot of the sulfuric acid is of the greatest importance since it permits of obtaining the acid by a liquid process and permits of the copper ore being refined at the mine itself, thus obviating transport of the acid. The acid is evidently produced at a very low cost, since it is manufactured in the electrolytic apparatus itself by means of sulfurous acid dissolved in the electrolyte and used for depolarization, this sulfurous acid itself being obtained by the roasting of copper ores when they are of the sulfid variety or from the roasting of pyrites when these are oxids or carbonates of copper.

What I claim is:—

An electrolytic apparatus, comprising

cathodes and anodes of rigid indestructible plates which are not acted upon by the current, composed of carbon or lead, said anodes having central portions forming circular disks and surrounding portions fixed in the same plane, said circular disks being mounted upon a horizontal shaft by means of which they are rotated in the plane of the fixed portion of the anodes, said cathodes 10 being constituted by plates of metal which

are suspended vertically between the anodes and are arranged symmetrically.

In witness whereof, I have hereunto signed my name in the presence of two subscribing witnesses.

MARCEL PERREUR-LLOYD.
